UNITED STATES PATENT OFFICE.

JAMES P. DOLAN, OF REVERE, MASSACHUSETTS, ASSIGNOR TO PENN METAL COMPANY, OF BOSTON, MASSACHUSETTS, A CORPORATION OF MASSACHUSETTS.

CULVERT.

1,110,047.

Specification of Letters Patent.

Patented Sept. 8, 1914.

Application filed April 15, 1914. Serial No. 832,023.

To all whom it may concern:

Be it known that I, JAMES P. DOLAN, a citizen of the United States, residing at Revere, county of Suffolk, State of Massachusetts, have invented a certain new and useful Improvement in Culverts, of which the following is a specification, reference being had therein to the accompanying drawings.

10 My invention has for its object a new and improved form of corrugated iron culvert, and particularly a culvert which can be conveniently shipped in nested condition and which can be assembled without the use 15 of tools. In culverts of this class as heretofore ordinarily constructed, it has been found that the projection of lips or edges from the sides of the two halves of the culvert practically prevent the culverts being 20 shipped in nested form, which is essential, as otherwise the expense for transportation is greatly increased. Also, where the two halves of the culvert have been secured together by a series of bolts projecting 25 through the wall of the culvert from the inside, it has been found to be a matter of considerable difficulty to assemble the culvert since it is necessary to bring the holes into accurate registration with each other 30 and to hold the head of the bolt on the inside of the culvert with some tool, as for instance a screw driver or pliers.

35 My invention affords a construction of culvert which can be conveniently and perfectly nested for shipment, and which can be assembled without the use of tools on the inside of the culvert. Furthermore, if it is desirable at any time to get at the interior 40 of the culvert after it has been installed, as for instance in case it should become clogged by mud or silt, this can be accomplished without removing any nuts or screws, which has been found practically impossible because the nut or screw had to be held on 45 the inside of the pipe, the ordinary procedure being to cut the bolt. The culvert embodying my invention is also constructed in such manner that leakage of water into the culvert from the outside is practically 50 impossible, and therefore silt is not so likely to accumulate in the interior of the culvert.

55 The invention will be fully understood by reference to the following description taken in connection with the accompanying drawings, and the novel features thereof are

clearly pointed out and distinctly claimed in the claim at the close of this specification.

In the drawings, Figure 1 is a side elevation of a section of culvert embodying my 60 invention. Fig. 2 is a transverse section on line 2—2 of the culvert shown in Fig. 1. Fig. 3 is a section on the line 3—3 of Fig. 1 on an enlarged scale. Fig. 4 is a horizontal section on line 4—4 Fig. 3. Fig. 5 65 shows the parts of the culvert separated.

Referring now to the drawings, the culvert consists of the upper and lower halves 11 and 12, each of which in the form shown in the drawings, is made of half round 70 pieces of corrugated iron. These halves are of sufficient peripheral length to overlap on the sides and form a culvert of substantially circular cross section.

At 13, is shown a longitudinal member 75 secured to the lower half 12 by means of bolts or rivets 14. This longitudinal member 13 is flat and does not follow the corrugations of the two halves of the culvert. It is made preferably with its upper edge 15 80 folded in as shown in Fig. 2 and its lower edge 16 inturned to form a triple thickness of metal at this point. By forming the longitudinal member as described, a space is formed between the lower half and the inside surface of the longitudinal member 85 within which the upper half is conveniently received. It will also be seen that the upper half 11 rests on the edge of the inturned portion 16, as shown in Fig. 3. 90

At 17, 18 are shown wire connecting members which extend around the periphery of the two halves of the culvert when assembled, being twisted together as shown at 18, Fig. 2. As will be readily understood, the 95 load on the upper half of the culvert rests on the upper edge of the inturned portion of the longitudinal member 13 and the flexible connecting members 17 do not carry any part of this load. It will also be seen that when the 100 culvert has been put in place and it is necessary for any reason to get at the interior of the culvert it is only necessary to disengage the ends of the flexible connecting member 17 and lift out the upper half. This can be 105 done without the use of tools and without reaching into the inside of the culvert or cutting the bolts or rivets, as has heretofore been frequently necessary. Should any of the bolts or rivets 14 become rusted or broken 110

by wear they may be readily replaced after the upper half 11 has been lifted off as explained. It will also be seen that any mud or silt which enters the space between the longitudinal member and the upper edge of the lower half will not pass into the interior of the culvert but will pass out through the space 19, see Fig. 4, between the longitudinal member and the corrugated 10 wall of the lower half 12.

What I claim is:

The improved culvert comprising a lower half and an upper half of corrugated metal, longitudinal members secured to each side 15 of one half, said longitudinal member having its lower edge composed of a plurality

of thicknesses of metal whereby a space for the reception of the upper half is left between the inner edge of the longitudinal member and the outer edge of the half to 20 which it is secured, said turned edge forming a support for the other half, bolts or rivets securing said longitudinal member and a flexible retaining member passing about said upper and lower halves. 25

In testimony whereof I affix my signature, in presence of two witnesses.

JAMES P. DOLAN.

Witnesses:

GEORGE P. DIKE,
ALICE H. MORRISON.
